(57) CLAIM

The ornamental design of a golf GPS device, as shown and described herein.

DESCRIPTION

FIG. 1 is a perspective view of a golf GPS device in accordance with an embodiment of the present invention;

FIG. 2 is another perspective view of a golf GPS device of FIG. 1;

FIG. 3 is a front view of the golf GPS device of FIG. 1;

FIG. 4 is a rear view of the golf GPS device of FIG. 1;

FIG. 5 is a left side view of the golf GPS device of FIG. 1;

FIG. 6 is a right side view of the golf GPS device of FIG. 1;

FIG. 7 is a top plan view of the golf GPS device of FIG. 1; and,

FIG. 8 is a bottom plan view of the golf GPS device of FIG. 1.

The broken lines in the Figures are for illustrative purposes only and form no part of the claimed design.
